United States Patent Office

Des. 195,798
Patented July 30, 1963

195,798

SUBMARINE

Philip A. Scoma, 6507 Vinevale Ave., Bell, Calif.

Filed Jan. 18, 1963, Ser. No. 73,230

Term of patent 14 years

(Cl. D71—1)

Fig. 1

Fig. 4

Fig. 2

FIGURE 1 is a side elevational view of a submarine showing my new design, the side opposite being substantially the same in appearance;

I claim:

The ornamental design for a submarine, as shown and described.
